UNITED STATES PATENT OFFICE.

WITMER J. KENDIG, OF LANCASTER, PENNSYLVANIA.

RAZOR OR BLADE STROPPING MACHINE.

933,465.

Specification of Letters Patent. Patented Sept. 7, 1909.

Application filed April 7, 1909. Serial No. 488,482.

To all whom it may concern:

Be it known that I, WITMER J. KENDIG, a citizen of the United States, residing at Lancaster, in the county of Lancaster and State of Pennsylvania, have invented certain new and useful Improvements in Razor or Blade Stropping Machines, of which the following is a specification, reference being had therein to the accompanying drawing.

10 My invention relates to improvements in a stropping machine or a device to be used for stropping razors or safety-razor blades, and it relates more particularly to that class of stropping devices having a flexible strop-band or "strop" of leather or other suitable material capable of sharpening razors or blades where all that the operator has to do is to reciprocate the strop, the rest of the 15 operation being automatically carried out by 20 the mechanism.

The objects of the invention are to provide a razor or blade stropping device by means of which razors or safety-razor blades may be stropped or sharpened, whenever necessary in a simple and effective manner, the blade always having the proper bight against the strop.

Another object of the invention is to produce a device of this class in which the razor 30 blade is stationary and the strop mounted in an oscillating frame or holder, which gives a more even bight and obviates all danger caused by the flopping of the razor handle, as is the case with other stropping devices 35 where the blade is oscillated.

Still another object of my device is to produce a stropping machine for double edged safety-razor blades where both of the edges may be sharpened at the same operation 40 without any readjustment or turning of the blade, which I believe is a feature not found in any other stropping machine.

With these and other objects in view my invention consists in certain combination 45 and construction of parts as will hereinafter be fully described and claimed in the appended specification and fully illustrated in the annexed drawings, which form a part of this application, and in which like figures of 50 reference refer to corresponding parts in all of the views, but it is fully understood that while I have here described my device as herewith illustrated, I do not confine myself to the exact design as shown, as slight 55 changes may be made in the construction

and combination without departing from the spirit of the invention.

Figure 1, is a side elevation of my stropping device as designed for use with ordinary razors, with part of the side plate 60 and strop removed, showing a razor in place. Fig. 2, is a sectional view of the same, taken on the line X—X of Fig. 1, showing the oscillating strop holder in its two extreme positions. Fig. 3, is a disassembled view of 65 the yoke and razor clamp, showing the method of joining the parts together. Fig. 4, is an end elevation of the device, with the razor and strop removed, showing the slots in the side of the yoke and the strop holder registering with each other in position to insert or withdraw the razor blade, and the dotted lines indicating the position of the strop holder when in use. Fig. 5, is a side elevation of my stropping device as 70 designed for double edged safety razor blades, showing a blade in place and part of the side plate and strop removed. Fig. 6, is a sectional view of the same, taken on the line Y—Y of Fig. 5, showing the oscillating strop holder in its extreme positions for 75 sharpening the blade. Fig. 7, is a partial view of the yoke to illustrate the slotted tube for the reception of the blade and rod. Fig. 8, is an end view of the same. Fig. 9, is a 80 top plan view of the tube, showing the blade securing slot. Fig. 10, is an end view of Fig. 5, with the razor blade and strop removed, showing the method of inserting or removing the blade. Fig. 11, is a detail 85 view of the razor blade-holding rod, with the blade removed therefrom. Fig. 12, is another view of the same, showing the blade-retaining studs.

Referring to the drawings:—In Figs. 1, 95 2, 3, and 4, the device comprises a yoke 1, supplied with a securing ring 2, and having the ends of its depending arms rigidly secured to the squared ends of a razor-holding rod 3, by the screws 4; said razor-holding 100 rod being provided with a spring blade-holding clamp 5. Mounted within said yoke and upon the projecting ends of said razor-holding rod 3, is an oscillating strop holder comprising the end plates 6, and 7, 105 which are joined together by the side plates 8, and the stay-rods 9, and said strop holder is further provided with the rollers 10, 11, and 12; the distance between the pivot point and the roller 10, being much greater than 110

that between said pivot point and either of the rollers 11, or 12. The strop 13, being passed over the roller 10, between the side plates 8, with one of its end portions between the roller 11, and the adjacent stay-rod 9, and the other end portion between the roller 12, and the adjacent stay-rod 9, it will thus be seen that by pulling first upon one end of the strop 13, and then upon the other end of said strop the holder will be oscillated and the strop brought into a bighting contact upon its upward movement with the edge of the razor blade 14, at a correct angle for sharpening, and which is always the same, and the strop 13, being further pressed against the blade 14, by the side plate 8. As the pull on the strop is reversed the holder is oscillated and the opposite side of the blade 14, sharpened. To insert the blade 14, into the holder 3, the end plate 7, of the strop holder is provided with a slot 15, which when the blade-holding clamp 5, and the strop holder plate 7, are brought into line will register with a corresponding slot in the yoke arm, so that as the blade 14, is being passed through these slots, the device is locked and the strop is in such a position that it cannot come into contact with the blade 14, and be damaged thereby, and the strop holder and yoke become locked until the blade is fully inserted into the clamp 5, and ready to be sharpened.

Referring to Figs. 5, 6, 7, 8, 9, 10, 11, and 12, of the drawings a slight modification of the device is shown, by which it is adapted to the double-edge safety blade, the difference being that the rod 3, is tubular in form and provided with a longitudinal slot 16, in its opposite sides and having its ends permanently secured to the side arms of the yoke 1, at a higher point than that employed in the device as used with ordinary razors, and the blade 14, is held in place by being placed on the rod 5, with the studs 17, engaging its orifices, and the rod 5, carrying the blade 14, is then inserted through the slots 15,

into the tubular rod 3, the edges of the blade 14, extending through the slots 16, in the sides of said tubular rod 3. The ends of the strop 13, in this case are placed on the outside of the rollers 11, and 12, and it will thus be seen that both of the edges of the blade are sharpened in the same way and at the same time without having to remove the blade or reverse it.

50 55

Having thus described my invention what I claim as new and desire to secure by Letters Patent is:—

1. In a razor-blade stropping device, the combination with a stationary frame formed with a tubular blade holder provided with a longitudinal slot in the opposite sides thereof, of a blade-holding rod provided with blade-retaining bosses and adapted to slide within said tubular blade holder with a portion of the blade carried thereby extending through said slots, a strop holder swingably mounted within said frame and means for bringing the strop into a sharpening contact with the surfaces of said blade by the action of said strop.

2. In a razor blade stropping machine of the class described, the combination with a yoke shaped stationary frame, of a blade-holding means rigidly secured between the arms of said yoke shaped frame, an independent blade-carrying means adapted to be inserted within said blade-holding means, a strop holder swingably mounted within said stationary frame and provided with strop-carrying and guiding rollers, and retaining side plates, slots formed in one end of said strop holder and in the adjacent arm of said yoke for the passage of the blade when said slots are in a registering position with each other.
